A. SHAPIRO

STEERING WHEEL LOCK

Filed Nov. 16, 1923

Patented June 10, 1924.

1,496,909

UNITED STATES PATENT OFFICE.

ABRAHAM SHAPIRO, OF CHICAGO, ILLINOIS.

STEERING-WHEEL LOCK.

Application filed November 18, 1923. Serial No. 275,301.

To all whom it may concern:

Be it known that I, Abraham Shapiro, citizen of the United States, residing at Chicago, in the county of Cook and State of

Illinois, have invented a certain new and useful Improvement in Steering-Wheel Locks, of which the following is a full, clear, concise, and exact description.

My invention relates to mechanism for preventing the steering mechanism of automobiles or other vehicles from functioning to guard against theft.

In the prior device, the steering wheel is locked against rotation by means of mechanism that cooperates directly with the steering wheel shaft. A cap is disposed upon the upper end of the hollow steering column, the skirt of the cap surrounding said column. The mechanism for holding the steering wheel and shaft against rotation is disposed in the cap. A key controlled lock serves to place the holding mechanism in non-functioning position, the arrangement being such that the holding mechanism may be instantaneously adjusted to function, without aid of the key lock and merely by hand pressure upon one of the members of the holding mechanism. It was possible to defeat the purpose of the prior device by means of hammer blows. I avoid this possibility by the device of my invention.

The invention will be fully explained by reference to the accompanying drawing in which Fig. 1 is a view in elevation of the device in assembly with a steering wheel which is shown in section, portions of the steering shaft and steering column being also shown; Fig. 2 is an axial sectional view in the region of the steering wheel; Fig. 3 is a view on line 3-3 of Fig. 2; and Fig. 4 is a view on line 4-4 of Fig. 2.

Like parts are indicated by similar characters of reference throughout the different figures.

The steering mechanism includes a steering shaft 1, a hollow stationary column 2 surrounding the shaft, and a hand steering wheel in driving relation to the shaft. In the structure illustrated the steering wheel has a stub shaft 4 that is in gear connection with the main shaft 1. The hand wheel turns the shaft 1 by means of the pinion 5 upon stub shaft 4, the planetary pinions 6 and the stationary internal gear 7 being and within the upper and enlarged end of the column 2. The planetary pinions are

mounted on the upper end of shaft 1 in which the lower end of stub shaft 4 is also journaled.

The stub shaft 4 is provided with holding formations that are employed when the shaft 1 is to be held against rotation. These holding formations preferably reside in extensions 57 of the teeth of the pinion 5 between which the toothed inner end of plunger 8 is receivable to lock the wheel. This plunger is horizontally and radially disposed in a cap 9 that is screwed upon column 2 and is held in rigid assembly with said column by a coupling pin 10, which is carried by the cap and is in threaded engagement with the cap and column, between and along which elements the pin is disposed.

The plunger 8 is pressed upon outwardly by a spring 11 which bears at its inner end against the cap and at its outer end against a holding formation upon the plunger 8, this holding formation being preferably in the form of a shoulder 12.

A plunger 13 is also carried by the cap, this plunger being beneath and angular to the plunger 8. An upright spring 14 has its upper end in engagement with the cap and its lower end in engagement with the shoulder or flange 13' on plunger 13. This spring presses downwardly upon the plunger 13 in a direction to move it downwardly, when spring 14 is free to act.

A second plunger 17 is carried by plunger 8 and is movable transversely thereof in a recess 18 provided therein. The upper end of plunger 17 is capped to receive a spring 19 whose upper end bears against plunger 8 to press the plunger 17 downwardly and into the recess in the cap 9 receiving the upper end of plunger 13 when plunger 8 is in its innermost and steering wheel holding position. The lower end of plunger 17 engages the upper end of plunger 13 when the plunger 8 is in its inner and steering wheel holding position. A key controlled lock 20 has an eccentric pin 21 received in an annular slot 22 in the plunger 13. When the steering mechanism is to be unlocked, the lock barrel is turned to bodily turn the pin 21 to raise the plunger 13 against the action of spring 14 to bring the lower end of plunger 17 flush with the bottom of the recess that contains the plunger 8, whereupon the spring 19 will disengage and push plunger 8 outwardly and out of holding relation to the shaft 4 and the steering wheel thereon.

- When the steering wheel is again to be locked, it is only necessary to press inwardly upon the plunger 8 until the teeth upon its inner end engage the teeth 5' at which time the plunger 17 is in register with the recess that receives the upper end of plunger 13, and is pressed into this recess by the spring 19, the plunger 13 having been either previously depressed by the operation of the key or by the spring 19. Plunger 17 thereupon holds plunger 13 in wheel locking position from which it may again be moved by operation of the lock, as hitherto described.
- 15 The springs 14 and 19 operating in conjunction with the plungers 13 and 17 prevent unlocking operation of these plungers by momentum due to hammer blows.
- The pin 10 is covered by plunger 8 when the plunger is in holding relation to the steering wheel. When plunger 8 is in its outer position the hole 23 in the plunger is in register with pin 10 or the space receiving it, so that the pin may be inserted or removed. A cap screw 24 is in line with the pin and the space receiving the pin and is removed when the pin is to be inserted or removed.
- A motion limiting pin 25 is carried by the cap 9 and enters the elongated recess 26 to limit the extent to which the spring 11 may thrust the plunger 8 outwardly.
- I do not wish to be limited to the precise details of construction shown, as changes may readily be made without departing from the spirit of my invention, but having thus described my invention, I claim as new and desire to secure by Letters Patent the following:—
- 40 1. Steering mechanism including a steering shaft; a hollow column containing said shaft; a cap upon said column and having a skirt surrounding it; mechanism in the cap for rigidly assembling it with the shaft to prevent the shaft from turning, said mechanism comprising an outwardly spring pressed plunger engageable at its inner end with a holding formation that is provided upon the shaft to prevent the shaft from turning and accessible at its outer end to be compressible toward the shaft, a second plunger carried by and angular to the first plunger; a spring also carried by the first plunger and pressing outwardly upon the second plunger whose outer end is receivable in a recess formed in said cap to lock the steering shaft; and a key controlled lock in adjusting relation to the second plunger to place it out of said recess to release the steering shaft from turning, said mechanism comprising a plunger engageable at its inner end with a holding formation that is provided upon the shaft to prevent the shaft from turning and accessible at its outer end to be compressible toward the shaft, a second plunger carried by and angular to the first plunger; a spring also carried by the first plunger and pressing outwardly upon the second plunger whose outer end is receivable in a recess formed in said cap to lock the steering shaft; and a key controlled lock in adjusting relation to the second plunger to place it out of said recess to release the steering shaft, said key controlled lock including a plunger transverse to the first aforesaid plunger and aligned with the recess in the cap that receives the outer end of the second plunger and operable to engage the outer end of the second plunger to push it out of this recess to permit the first plunger to have its locking connection with the steering shaft broken.
- 45 2. Steering mechanism including a steering shaft; a hollow column containing said shaft; a cap upon said column and having a skirt surrounding it; mechanism in the cap for rigidly assembling it with the shaft to prevent the shaft from turning, said mechanism comprising a plunger engageable at its inner end with a holding formation that is provided upon the shaft to prevent the shaft from turning and accessible at its outer end to be compressible toward the shaft, a second plunger carried by and angular to the first plunger; a spring also carried by the first plunger and pressing outwardly upon the second plunger whose outer end is receivable in a recess formed in said cap to lock the steering shaft; and a key controlled lock in adjusting relation to the second plunger to place it out of said recess to release the steering shaft, said key controlled lock including a plunger transverse to the first aforesaid plunger and aligned with the recess in the cap that receives the outer end of the second plunger and operable to engage the outer end of the second plunger to push it out of this recess to permit the first plunger to have its locking connection with the steering shaft broken.
- 50 3. Steering mechanism including a steering shaft; a hollow column containing said shaft; a cap upon said column and having a skirt surrounding it; mechanism in the cap for rigidly assembling it with the shaft to prevent the shaft from turning, said mechanism comprising a plunger engageable at its inner end with a holding formation that is provided upon the shaft to prevent the shaft from turning and accessible at its outer end to be compressible toward the shaft, a second plunger carried by and angular to the first plunger; a spring also carried by the first plunger and pressing outwardly upon the second plunger whose outer end is receivable in a recess formed in said cap to lock the steering shaft; and a key controlled lock in adjusting relation to the second plunger to place it out of said recess to release the steering shaft, said key controlled lock including a plunger transverse to the first aforesaid plunger and aligned with the recess in the cap that receives the outer end of the second plunger and operable to engage the outer end of the second plunger to push it out of this recess to permit the first plunger to have its locking connection with the steering shaft broken.
- 55 4. Steering mechanism including a steering shaft; a hollow column containing said shaft; a cap upon said column and having a skirt surrounding it; mechanism in the cap for rigidly assembling it with the shaft to prevent the shaft from turning, said mechanism comprising a plunger engageable at its inner end with a holding formation that is provided upon the shaft to prevent the shaft from turning and accessible at its outer end to be compressible toward the shaft, a second plunger carried by and angular to the first plunger; a spring also carried by the first plunger and pressing outwardly upon the second plunger whose outer end is receivable in a recess formed in said cap to lock the steering shaft; and a key controlled lock in adjusting relation to the second plunger to place it out of said recess to release the steering shaft, said key controlled lock including a plunger transverse to the first aforesaid plunger and aligned with the recess in the cap that receives the outer end of the second plunger and operable to engage the outer end of the second plunger to push it out of this recess to permit the first plunger to have its locking connection with the steering shaft broken.
- 60 5. Steering mechanism including a steering shaft; a hollow column containing said shaft; a cap upon said column and having a skirt surrounding it; mechanism in the cap for rigidly assembling it with the shaft to prevent the shaft from turning, said mechanism comprising a plunger engageable at its inner end with a holding formation that is provided upon the shaft to prevent the shaft from turning and accessible at its outer end to be compressible toward the shaft, a second plunger carried by and angular to the first plunger; a spring also carried by the first plunger and pressing outwardly upon the second plunger whose outer end is receivable in a recess formed in said cap to lock the steering shaft; and a key controlled lock in adjusting relation to the second plunger to place it out of said recess to release the steering shaft, said key controlled lock including a plunger transverse to the first aforesaid plunger and aligned with the recess in the cap that receives the outer end of the second plunger and operable to engage the outer end of the second plunger to push it out of this recess to permit the first plunger to have its locking connection with the steering shaft broken.

- lock also including a plunger transverse to the first aforesaid plunger and aligned with the recess in the cap that receives the outer end of the second plunger and operable to engage the outer end of the second plunger to push it out of this recess to permit the first plunger to have its locking connection with the steering shaft broken.
5. Steering mechanism including a steering shaft; a hollow column containing said shaft; a cap upon said column and having a skirt surrounding it; mechanism in the cap for rigidly assembling it with the shaft to prevent the shaft from turning, said mechanism comprising an outwardly sprung pressed plunger engageable at its inner end with a holding formation that is provided upon the shaft to prevent the shaft from turning and accessible at its outer end to be depressed toward the shaft, a second plunger carried by and angular to the first plunger; a spring also carried by the first plunger and pressing outwardly upon the second plunger whose outer end is receivable in a recess formed in said cap to lock the steering shaft; and a key controlled lock in adjusting relation to the second plunger to place it out of said recess to release the steering shaft, said key controlled lock also including a plunger transverse to the first aforesaid plunger and aligned with the recess in the cap that receives the outer end of the second plunger and operable to engage the outer end of the second plunger to push it out of this recess to permit the first plunger to have its locking connection with the steering shaft broken, and a spring pressing upon the plunger of the key controlled lock away from the second plunger.
6. Steering mechanism including a steering shaft; a hollow column containing said shaft; a cap upon said column and having a skirt surrounding it; mechanism in the cap for rigidly assembling it with the shaft to prevent the shaft from turning, said mechanism comprising a plunger engageable at its inner end with a holding formation that is provided upon the shaft to prevent the shaft from turning and accessible at its outer end to be depressed toward the shaft, a second plunger carried by and angular to the first plunger; a spring also carried by the first plunger and pressing outwardly upon the second plunger whose outer end is receivable in a recess formed in said cap to lock the steering shaft; and a key controlled lock in adjusting relation to the second plunger to place it out of said recess to release the steering shaft, said key controlled lock also including a plunger transverse to the first aforesaid plunger and aligned with the recess in the cap that receives the outer end of the second plunger and operable to engage the outer end of the second plunger to push it out of this recess to permit the first plunger to have its locking connection with the steering shaft broken, and a spring pressing upon the plunger of the key controlled lock away from the second plunger.

In witness whereof, I hereunto subscribe my name this seventh day of November, A. D., 1923.

ABRAHAM SHAPIRO.
